UNITED STATES PATENT OFFICE.

CHARLES H. LEHMAN, OF NEW YORK, N. Y.

DESIGN FOR A RADIO LOUD SPEAKER.

Application filed November 29, 1922. Serial No. 4,452. Term of patent 7 years.

To all whom it may concern:

Be it known that I, CHARLES H. LEHMAN, a citizen of the United States, and a resident of the city of New York, in the borough of Manhattan and State of New York, have invented a new, original, and ornamental Design for a Radio Loud Speaker, of which the following is a specification, reference being had to the accompanying drawings, forming part thereof, wherein—

Fig. 1 is a front view of a radio loud speaker embodying my new design;

Fig. 2 is a side view thereof; and

Fig. 3 is a rear view.

I claim:

The ornamental design for a radio loud speaker as shown.

CHARLES H. LEHMAN.
